Isaac Dillies Design for Stoves.

No. 801.

Patented June 11, 1866.

Des. 801

Isaac Diller of Lancaster, Pa,
Letters Patent No. 801, Dated June 17th 1856.

The schedule referred to in these Letters Patent and making part of
the same.

To all whom it may concern:

Be it known that I, Isaac Diller, of the City and
County of Lancaster, and State of Pennsylvania, have invented or produced
a new, useful and ornamental design for a parlor oven stove; And
I do hereby declare that the same is described and represented in the
following specifications and drawings:

To enable others skilled in the art, to make and
use my ornamental design, I will proceed to describe it referring to the
drawing which represents the front of the stove with the design upon

it, which I wish to secure by Letters Patent. The lower portion of this design consists of three panels A, A, A, formed by heavy mouldings in bass-relief surmounted with gothic arches as shown in the drawing. The ground of these panels is nearly covered with pyramids B, having the sides of their bases arranged diagonally to the bottom and sides of the panel.

Between the tops of the arches abovementioned, there are two figures C, C, which are made by depressing the surface a little in the form shown.

There are also two triangular ornamental figures D, D, a little distance from the outside arches made in the form shown by depressing the surface as above mentioned.

The main ground is crossed by two beads E, E, in bass relief at some distance apart, between which beads there are two ornamental open work door frames F, F, made in the form shown and arranged to slide behind the squares G, G, which squares are ornamented with pyramids arranged as shown, surrounded by scrolls as represented in the drawing.

Above the upper bead E, there is a series of ornaments and panels containing pyramids similar to the ornaments and panels below the lower bead E, except that the panels are longer and contain more pyramids with one in the centre at H, which is omitted in the lower panels.

What I claim as my invention and desire to secure by Letters Patent, is the arrangement and combination of ornaments, which form the design above described for a parlor oven stove.
